FOOTWEAR SOLE

Thomas H. Doherty, South Bend, Ind., assignor to Mishawaka Rubber Company, Inc., Mishawaka, Ind., a corporation of Indiana

Filed July 11, 1960, Ser. No. 61,303

Term of patent 14 years

(Cl. D7—5)

FIG. 1 is a plan view of a footwear sole embodying my design;

FIG. 2 is a sectional view taken substantially on the plane indicated by line II—II of FIG. 1; and

FIG. 3 is a sectional view taken substantially on the plane indicated by line III—III of FIG. 1.

I claim:

The ornamental design for a footwear sole, substantially as shown.
